UNITED STATES PATENT OFFICE

ROBERT EDWARD PHILLIPS AND ERNEST RICHARD SHIPTON, OF LONDON,
COUNTY OF MIDDLESEX, ENGLAND.

BROOCH OR BADGE FOR CLUBS.

SPECIFICATION forming part of Letters Patent No. 350,079, dated September 28, 1886.

Application filed May 24, 1886. Serial No. 203,167. (No model.) Patented in England July 14, 1885, No. 8,518, and in France April 16, 1886, No. 162,843.

To all whom it may concern:

Be it known that we, ROBERT EDWARD PHILLIPS and ERNEST RICHARD SHIPTON, subjects of the Queen of Great Britain, residing at London, in the county of Middlesex, England, have invented certain new and useful improvements in and relating to brooches or badges for clubs and other bodies whose membership is defined by the payment of periodical subscriptions, (for which we have obtained Letters Patent in England, No. 8,518, dated July 14, 1885, and in France, No. 162,843, dated April 16, 1886,) of which the following is a specification.

Our invention relates to the construction of brooches or badges for the use of clubs and other bodies as an outward and visible mark of membership, and has for its object the prevention of fraud by any one wearing the brooch or badge of a club after ceasing to be a member.

At the present time there are three different methods of supplying the members of clubs with badges, all of which have objections more or less grave.

First. The badges are sold direct to the members, which therefore become their own property, and they can consequently, though fraudulently, wear them after ceasing to be members.

Secondly. The badges are lent to members either with or without a deposit. This system requires a considerable expenditure of capital on the part of the club without any corresponding return, and it is a difficult matter to get the badges returned by persons who have ceased to be members.

Thirdly. Badges of a new design are issued each year to the members. This is objectionable on the ground of cost, as members cannot be expected to purchase new badges at frequent intervals, while the cost of distributing them gratis cannot be borne by other than large and influential clubs.

By the use of brooches or badges constructed according to our invention all these difficulties are removed, as the brooches or badges cease to be a distinctive token of membership unless the periodical subscription is paid.

To attain this end we construct our brooches or badges of two parts, one of which forms the ticket of membership and is renewable at stated intervals, defined by the period covered by the subscription. The two parts of the badge are designed to harmonize with each other and form any suitable design. The part forming the ticket of membership is preferably formed of some cheap and inexpensive material, which is capable of receiving writing on at least one side, and which is impervious to heat and moisture. The other part of the badge is preferably made of precious metal or imitation thereof. We make the metal part in the shape of a case to receive the renewable or changeable part constituting the ticket of membership. The renewable part of the badge is made in different colors or combination of colors each year or other period of membership, and bears on the face of it some distinctive mark—such as the number of the year—while the back of it is left blank to receive any official markings, and the name and address of the member to whom it is issued. It will thus be seen that the metal or case part of the brooch or badge may be sold to the members, as until the ticket of membership is placed within it it does not become the official badge, while the renewable part or ticket can be produced as cheap as any of the present forms of membership tickets, and may therefore be distributed gratuitously.

In the accompanying drawings, throughout the figures of which similar parts are marked with like letters of reference, Figures 1, 2, 3, 4, and 5 illustrate a design for a brooch or badge suitable for cycling-clubs. Fig. 1 is a view of the brooch or badge complete. Fig. 2 is a view of the metal case open showing the back of the ticket of membership. Fig. 3 is a view showing the front of the renewable part or ticket of membership. Fig. 4 is a sectional view of the badge complete, and Fig. 5 is a sectional view of the renewable part.

Referring to these figures, A designates the metal case part of the brooch or badge, and B the renewable part forming the ticket of membership. The front of the case A is made to

represent a cycle-wheel, the spokes of which form filigree-work. The face of the disk B is provided with a series of radial grooves forming an intaglio, which coincides with the relief of the filigree-work of the front of the case. 5 The back of the case may be cut away, as shown, or it may be of filigree-work, like the front. The front of the disk B is colored, and the number of the year, or some other distinctive mark, is made in some other color or tint. The back of the disk may also be colored, if desired; but we prefer to leave it plain, so that the official markings may be plainly visible.

5 Figs. 6, 7, 8, 9, and 10 illustrate a design for a badge for trotting, horse-racing, or analogous clubs. Fig. 6 is a view of the brooch or badge complete. Fig. 7 is a view showing the case open. Fig. 8 is a view showing the front of the renewable or ticket-of-membership part. Fig. 9 is a sectional view of the complete badge, and Fig. 10 is a sectional view of the renewable or ticket-of-membership part.

25 Referring to these figures, A designates the metal case part of the brooch or badge, and B the renewable part forming the ticket of membership. The front of the case A represents the shoe of a horse and the renewable part B the hoof of a horse, so that when the two are 30 together it forms a harmonious design of the shod hoof of a horse.

The brooch or badge may be provided with any suitable device for attaching it to the person of the wearer, as it is intended to be worn 35 as a brooch, badge, pin, or appendage to the watch-chain.

It will be obvious that our improved brooches or badges may be used and are applicable to other bodies than cycling, trotting, 40 and other athletic clubs—as, for instance, they

may be used by railway companies for season-tickets, in which case the open or filigree work forming either or both the front and back of the case would define the arms or initials of the company, while the renewable part forming the ticket would be made of various colors to denote the various periods of payment, and the different classes would be denoted by various 45 stipes or other markings on the different colors. The faces of the ticket would be available for the markings for purposes of identification. As these badges may be appended or carried on the watch-chain, they would always be at hand and may readily be shown when required. 50

By the use of brooches or badges constructed according to our invention clubs and other bodies can insure themselves against members wearing their distinctive mark without first paying their subscriptions, as until they are 55 supplied with a ticket of membership they cannot make their brooch or badge complete.

What we claim as our invention, and desire to secure by Letters Patent, is—

A club brooch or badge consisting of an inclosing-case of any desired design, formed partly in open work, and a renewable card placed within the case and having a corresponding design on it in intaglio, registering with the said open work of the case, and bearing, also, an inscription indicating the term of membership of the wearer. 65

In witness whereof we have hereunto signed our names in the presence of two subscribing witnesses.

ROBERT EDWARD PHILLIPS.
ERNEST RICHARD SHIPTON.
